UNITED STATES PATENT OFFICE.

ELMER E. PERKINS, OF CHICAGO, ILLINOIS.

DRYING-ROOM.

1,036,323.

Specification of Letters Patent. Patented Aug. 20, 1912.

Application filed April 15, 1912. Serial No. 690,998.

To all whom it may concern:

Be it known that I, ELMER E. PERKINS, a citizen of the United States, residing at Chicago, in the county of Cook and State of Illinois, have invented certain new and useful Improvements in Drying-Rooms, of which the following is a specification.

This invention relates in general to drying kilns and more particularly to the drying room itself and has, for one of its primary objects, the provision of a drying room equipped with drying apparatus which will be cheap to install, efficient in its operation and which can be regulated to a fine degree of nicety to produce the required temperature, air circulation and humidity necessary for the drying of articles or materials of various characters.

The invention will be best understood by reference to the following description when considered in connection with the accompanying drawings, the single figure of which shows a perspective view of a drying room embodying one form of the invention.

From the drawings it will be observed that the room proper comprises a plurality of walls 5, 6, 7 and 8 spaced apart to provide dead air insulating spaces surrounding the room. Obviously, the construction of the walls may vary widely in different installations, the particular structure disclosed in the present instance being merely illustrative, the object of the wall construction being to provide a room with heat insulating walls which will prevent dissipation and loss of heat from the interior of the room. The floor 9, which may be of any preferred construction, may be equipped with rails upon which cars of material may be transported to and from the room, or suitable racks or hangers may be provided within the room upon which the material to be dried may be supported. These mechanical details, however, will be made in each instance to conform to the requirements of the particular material or articles to be dried.

The heat is supplied to the room by means of coils 10 supported on suitable brackets 11 on one of the side walls adjacent the floor. The coils are preferably supplied with steam from any suitable source of supply which furnishes the required heat and the proper temperature is maintained within the room by a controlling valve 12 auto-

matically controlled from a suitable thermo-stat 13. The required humidity may be maintained by opening the hand operated valve 14 located in a pipe 15 connected with the coils, through which steam may be admitted to the interior of the room, if desired. The air which is heated by the coil 10 will rise and the air along the floor of the room will flow toward the coil to replace the heated air, a circulation within the room being thereby set up. In order to further assist in the maintenance of the proper circulation of air I have mounted on the opposite side of the room from the heating coil a cooling coil 16 through which cold water or brine is circulated by any suitable mechanism. The air which is cooled by the coil 16 will, of course, drop to the bottom of the room where it will flow along the floor to the opposite wall to be heated by the coil 10, whereupon it will rise again. A continuous circulation of air is thereby maintained within the room and the articles or material located therein will be dried under the most favorable conditions.

Many articles and materials such as macaroni and other flour products can not be dried under a high temperature because of certain changes which take place in their structure and composition when subjected to high heat. The rapidity, therefore, with which said articles can be dried under moderate temperature will depend upon the rapidity of the air circulation within the drying room. Other articles such as leather, rubber and various pigments which also require a low drying temperature need to be dried relatively slowly in order to prevent cracking of the surface or injury to the article. It is essential, therefore, if the room is to be used for various articles that the circulation be regulated to conform to the particular article being dried. It will be manifest that the rapidity of the circulation will depend upon the height of the cooling coil 16 above the floor, since the higher the coils are located the faster the cool air will fall and the more rapid will be the circulation within the room. I, therefore, prefer to mount the cooling coil brackets 17 upon upright pipes or standards 18 and to support the brackets at the required height by adjustable collars 19. The ends of the coil are connected with the cooling liquid supply by

flexible tubing 20 or suitable flexible pipe couplings which will permit the coil to be adjusted to various heights on the standards 18. On the drawings the cooling coil is shown, in full lines as adjusted to a position near the ceiling which will produce a rapid circulation and, in dotted lines as adjusted to a position near the floor which will produce a much slower circulation. Manifestly 10 the coil may be positioned at any intermediate point to produce the circulation required for the most successful drying of any particular article or articles, or material.

I have found that by simply adjusting the 15 height of the cooling coil the circulation of air within the drying room may be regulated to a fine degree of nicety without the employment of fans, forced drafts, or other expensive and complicated mechanisms or structures and my improved room equipped as 20 above described may be utilized for successfully drying articles or materials of widely different characters. In some instances where particularly delicate articles are to be 25 dried it may be found desirable to position a small screen in front of the heating coil to prevent direct radiation from the coil to the articles but, ordinarily, such a screen is unnecessary.

30 Many variations in details of construction will readily suggest themselves to those skilled in the art but it will be understood from the foregoing that the illustrative construction shown and described is capable of 35 considerable modification without departing from the spirit of the invention or sacrificing any of the material advantages thereof.

I claim:

1. A drier comprising a closed drying chamber having means for creating and maintaining a complete circuit of air circulation within the drying space of said closed chamber, said means including a heating device within the drying space and at one of the upright sides only of the chamber, and a cooling device within the drying space and at the opposite upright side only of the chamber with its cooling surface in direct contact with the air of the drying space, substantially as described. 50

2. A drier comprising a closed drying chamber having means for creating and maintaining a complete circuit of air circulation within the drying space of said chamber, said means including a heating device 55 within the drying space of said chamber, and a cooling device within the drying space of said chamber with its cooling surface in direct contact with the air of said drying space, and means whereby one of said devices may be supported at different elevations to change the rate of circulation of the air, substantially as described. 60

3. A drying room having heating means located adjacent one wall and near the floor, 65 cooling means located adjacent the opposite wall, and means whereby the cooling means may be supported at different elevations to regulate the circulation of air within the room, substantially as described.

ELMER E. PERKINS.
